United States Patent Office.

A. C. RAND, OF NEW YORK, N. Y.

Letters Patent No. 79,081, dated June 23, 1868.

IMPROVEMENT IN GAS-BURNERS.

The Schedule referred to in these Letters Patent and making part of the same.

TO ALL WHOM IT MAY CONCERN:

Be it known that I, A. C. RAND, of the city, county, and State of New York, have invented a new and useful Improvement in Gas-Burners; and I do hereby declare that the following is a full, clear, and exact description thereof, which will enable others skilled in the art to make and use the same, reference being had to the accompanying drawings forming part of this specification, in which—

Figure 1 represents a central vertical section of my improved gas-burner.

Figure 2 is a similar view of a modification of the same.

Figure 3 is a similar view of another modification of the same.

Figure 4 is a plan or top view of the latter modification.

Similar letters of reference indicate corresponding parts.

This invention relates to a new manner of constructing gas-burners of that class in which the gas issues through a long narrow slot, and consists in making the width of the aperture adjustable, so that a larger or smaller jet may be discharged from the burner, as may be desired.

The quality of the gas is subject to considerable variation, which is caused partly by changes of temperature, by the quality of the material from which the gas is produced, and by various other causes; and it is therefore a desideratum to have the size of the jet under control, so that a desired light may be obtained.

A, in the drawing, fig. 1, represents a gas-burner, in which one cheek, *d*, of the slot *a* is formed by the end of a screw, *b*, which can be screwed near to or further from the opposite fixed cheek *c*, whereby the width of the slot is decreased or enlarged at will.

B, fig. 2, represents a gas-burner, in which one cheek of the slot *a* is formed by a sliding block, *d*, which can, by means of a screw, *g*, that is swivelled either in the other cheek *c*, or in a projection formed on the outside of the burner, be moved to or from the cheek *c*, at will, with the aforesaid result.

C, in figs. 3 and 4, represents a similar burner as fig. 2, with the exception that the movable cheek *d* works on a spiral horizontal track, *e*, which is eccentric to the burner, and which is formed on a sleeve, *f*, that turns around the burner, and which, as it is turned, causes the block *d* to be moved towards or away from the opposite fixed cheek *c*, as may be desired, with the same aforesaid result.

The track on the sleeve *f* may either be formed by a slot, as shown, into which a pin projecting from the block *d* fits, or in any other suitable manner.

Other modes of adjusting the movable cheek may be employed, with equal success.

Having thus described my invention, what I claim as new, and desire to secure by Letters Patent, is—

A gas-burner, in which a movable cheek is adjustable towards or away from the stationary cheek, as herein described for the purpose specified.

A. C. RAND.
